UNITED STATES PATENT OFFICE

JOHN HAYS HAMMOND, JR., OF GLOUCESTER, MASSACHUSETTS

PIANO WITH TONE MODULATORS

Application filed December 10, 1928. Serial No. 325,014.

This invention relates to musical instruments of the percussive type, and more particularly to a mechanism for controlling the tone of such instruments.

- 5 The invention provides a plurality of adjustable shutters which are positioned adjacent the various strings of the instrument and are adapted to control the volume of sound emitted.
- 10 An object of the invention is to provide means for obtaining a predetermined distribution of the tone over the various parts of the musical scale.

Another object is to provide for the emission of a given minimum volume of sound when the shutters are in closed position.

A further object is to provide mechanism for completely closing the sound chamber at the will of the operator.

20 A still further object is to provide sound control mechanism which is capable of operating with substantially equal efficiency over the various portions of the scale.

The above objects and others which will be apparent as the nature of the invention is disclosed are accomplished by providing shutters of varying thickness over the different portions of the musical instrument. The thickness of the shutters is graduated

30 from the bass to the treble end of the instrument, the thickest portion being positioned at the bass end where the greatest volume of sound ordinarily is produced. In order to equally affect sound from the various parts of

35 the instrument, the shutters at the bass end where the wave length of the vibrations is greatest are spaced the longest distance from the source of sound, the distance gradually decreasing as the treble end is approached.

40 Adjustable openings are provided in certain shutters, preferably at the treble end, to insure the emission of a predetermined volume of sound when the shutters are in closed position. Mechanism is also provided for closing these openings when desired by the operator.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a top plan view of a piano provided with shutters and operating mechanism therefor in accordance with the present invention;

Fig. 2 is a front elevation partly in section 65 of the piano shown in Fig. 1;

Fig. 3 is a detail view of a portion of the operating mechanism;

Fig. 4 is a plan view of one of the modulators or shutters at the treble end;

Fig. 5 is a section taken on the line 5—5 of Fig. 4 showing the closure for the shutter; and

Fig. 6 is a view similar to that of Fig. 5 showing the sound aperture in completely 75 closed position.

Like reference characters denote like parts in the several figures of the drawings.

In the following description and in the claims parts will be identified by specific 80 names for convenience, but they are intended to be as generic in their application to similar parts as the art will permit.

Referring to the drawings more in detail, the system is shown as applied to a piano 85 10 which is provided with the usual strings 11 mounted in a frame 12 and is provided with a standard piano action 13 which is operated in the usual manner by keys 14. The piano is provided with three pedals 15, 16 and 17 which are mounted in a block 18 suspended from the framework of the piano by two uprights 20 and 21. Pedals 16 and 17 control the sostenuto and loud pedal action of the piano in a well known manner. Pedal 15 when depressed elevates rod 22, the upper end of which engages bell crank 23, said crank being pivoted as by pin 24 to the framework of the piano. Said bell crank 23 is operatively connected to an arm 30 by means of 100

link 25. Spring 26, secured between link 25 and a bracket 27 on the framework of the piano, controls the position of said link for maintaining the shutters, about to be described, in their closed position.

Arm 30 is rigidly secured to shaft 31 which is mounted for rotation in bearings 32 and 33 and is provided with a collar 34' which prevents longitudinal movement thereof. 10 Rigidly secured to shaft 31 are arms 34 and 35 to which are connected links 36 and 37 respectively. Said links are secured to rods 40 and 41 respectively which slide in collars 44 and 52.

15 The movement of rod 40 in collars 44 is limited by collars 42 and 43 which are rigidly secured on said rod. Springs 45 normally maintain collars 43 and 44 in contact and the rod in the position shown in Fig. 3.

20 Collars 44 are pivotally secured to arms 46 which are carried by the pivoted tone modulators 47. Said modulators are mounted for rotation about their longitudinal axis in the frame of the piano in any desired manner.

25 Rod 41 is slidably secured in collars 52 which are pivoted to arms 54, said arms being carried by an equal number of tone modulators 55 which are mounted for rotation in the framework of the piano about their longitudinal axis. Movement of rod 41 is limited by collars 50 and 51 which are secured thereto and the normal position of said rod is controlled by springs 53 which operate between 35 collars 50 and 52.

30 The various tone modulators 55 are of a thickness varying uniformly from the bass to the treble end of the piano, the thickest modulators being located at the bass end. 40 Said modulators are also mounted at an angle with respect to the plane of the strings of the piano, and the sounding board thereof, the modulators over the treble end being nearer to the strings than those over the bass end.

45 Certain of the tone modulators over the treble end are provided with openings 57 which may be closed by sliders 58, adapted to slide in suitable guides 59. The under-surface of the tone modulator adjacent the opening 57 is provided with a groove 61 in which normally rests the curved member 62 which is secured at its end to pivoted arms 63 and 64. Arm 64 is provided with a slot 67 in which pin 68 carried by collar 69 is adapted 55 to slide. Collar 69 is rigidly secured to rod 41 in any suitable manner.

60 In the operation of the device above described, the tone modulators are normally held in open position by means of spring 26. 65 When the pedal 15 is depressed, the rod 31 is rotated and through rods 40 and 41 causes pivotal movement of the various tone modulators, thereby bringing them into closed position. After said modulators have been fully 63 closed, pedal 15 may be still further depressed

thereby moving rods 40 and 41 against the tension of strings 45 and 53, causing said rods to slide in collars 44 and 52. Pin 68 thereupon cooperates with slot 67 in arm 64 and causes pivotal movement of curved member 62, thereby bringing the same into the position shown in Fig. 6 and completely closing the tone modulators.

70 In this way, after the tone modulators have been closed by the action of the pedal, the slots may also be closed by a further depression of said pedal. When the pressure on the foot pedal is released a reverse action takes place, first opening the various slots and then allowing the tone modulators themselves to open. It is accordingly possible to open and close the slots of the tone modulators without changing the adjustment of the sliders 58 which may have been carefully adjusted 80 to give the proper openings over certain strings to produce the desired effect in the piece being played.

85 While certain novel features of the invention have been shown and described and are pointed out in the annexed claims, it will be 90 understood that various omissions, substitutions and changes in the forms and details of the device illustrated and in its operation may be made by those skilled in the art without departing from the spirit of the invention. 95

What is claimed is:

100 1. In a musical stringed instrument, means for controlling the production of sound comprising a casing having openings therein, a plurality of normally open closures for said openings, means for simultaneously operating said closures, and means for modifying the action of certain of said closures, to vary the volume of sound emitted over a portion 105 only of a musical scale.

110 2. In a musical stringed instrument, means for controlling the production of sound comprising a casing having openings therein, a plurality of normally open closures for said openings, means for simultaneously operating said closures, means for modifying the action of certain of said closures to vary the volume of sound emitted over a portion only of a musical scale, and a single pedal for actuating said closures and subsequently actuating said modifying means. 115

120 3. In a musical stringed instrument, a plurality of strings tuned to the notes of a musical scale, a casing for said instrument having sound openings, a plurality of closures therefor, the closures adjacent the strings tuned to the lower notes being spaced further therefrom than the closures adjacent the strings tuned to the higher notes, and means for actuating said closures for variably controlling the intensity of the sound emitted by said instrument. 125

130 4. In combination with a stringed musical instrument, a casing therefor having sound

openings therein, a plurality of closures for said openings, said closures being of uniformly varying thickness from the bass to the treble end of said instrument.

5. In combination with a stringed musical instrument, a casing therefor having sound openings therein, a plurality of closures for said openings, said closures being of uniformly varying thickness from the bass to the 10 treble end of said instrument, the closures of greater thickness being located near said bass end.

6. In combination with a stringed musical instrument, a casing therefor having sound 15 openings, closures for said openings, certain of said closures having slots therein, and adjustable means for closing said slots.

7. In a stringed musical instrument, a casing having sound openings, tone modulators for closing said openings, certain of 20 said modulators having a slot therein, and means for closing said slot after said modulators have been brought into closed position.

8. In combination with a stringed musical 25 instrument, a casing therefor having a sound opening, a closure for said opening comprising tone modulators, certain of said modulators having slots, adjustable closures for said slots, and mechanism independent of 30 said closures for completely closing said slots after said modulators have been brought into closed position.

9. In combination with a stringed instrument, a casing therefor, tone modulators pivotally secured in said casing, certain of said 35 modulators located adjacent the treble end of said instrument having apertures therein, means for controlling the position of said modulators, and means for controlling the size of opening of said aperture.

40 In testimony whereof I have hereunto set my hand.

JOHN HAYS HAMMOND, JR.
